Attorneys.

UNITED STATES PATENT OFFICE.

JAMES H. RAND, JR., OF NORTH TONAWANDA, NEW YORK.

INDEX OR DISPLAY FRAME.

1,318,506.

Specification of Letters Patent. Patented Oct. 14, 1919.

Application filed September 15, 1915. Serial No. 50,889.

To all whom it may concern:

Be it known that I, JAMES H. RAND, Jr., a citizen of the United States, and resident of North Tonawanda, in the county of Niagara and State of New York, have invented new and useful Improvements in Index or Display Frames, of which the following is a specification.

This invention relates to index or display devices of the kind having a series of stiff frames or leaves hinged to a support, and its object is to provide means whereby the frames or leaves may be opened wide and flat relatively to each other, notwithstanding the frames or leaves are numerous and crowded and are stiff and inflexible. This is accomplished by the use of a hinge having two pivoted axes connecting each frame with the common support, as hereinabove described.

In the accompanying drawings which illustrate one embodiment of the invention,—

Figure 1 is an elevation of an index or display device containing the invention;

Fig. 2 is a fragmentary view, in plan, of said device; and

Fig. 3 is a detail of one end of the intermediate frame.

The support, as herein shown, consists of a standard comprising the post *a*, at the top and bottom of which are disks *b* having a series of pivot pin sockets *c*.

The swinging frames *d* are rigid panels or leaves for the display of index cards or other matter. Each display frame carries at its inner edge a pair of pivot pins or hooks *e*, one at the top and one at the bottom.

Between each display frame and the support, is an intermediate frame pivotally connected at its inner edge to the support and at its outer edge to the leaf or panel. Each intermediate frame, as herein shown, comprises a pair of hinge members *f*, *f*, one at the top and one at the bottom, and a brace, preferably consisting of a plate or bar *g*, rigidly uniting the hinge members *f*, *f*. The two hinge members *f*, *f*, are preferably identical, and each has a hook or pivot pin *h* at its inner end, to engage one of the sockets *c* of the support, and a socket *i* at its outer end to receive the pivot pin *e* of the display frame.

The intermediate frame is readily remov-

able from the support by merely lifting the pivot pins *h* out of the sockets *c*, and the display frames are similarly removable from the intermediate frames. Thus the corresponding parts are interchangeable, 60 the intermediate frames may be applied to index or display devices already in use, and the intermediate frames and display frames may be applied to supports of various sizes and shapes; for it will be understood that 65 the invention is by no means limited to the circular form of support shown.

In a device of this type, using stiff and inflexible leaves hinged close together it is impossible to open out two adjacent leaves 70 sufficiently wide and flat to secure the maximum of convenience and facility in using the device. But with the double pivot hinge of the present invention a much wider opening of the leaves is possible. As the top 75 and bottom hinge members are rigidly connected the device as a whole loses nothing in rigidity; the intermediate frames may be easily applied to index and display devices now in common use; and all the parts being removable the intermediate frames may be removed and the display frames directly mounted on the support, if so few leaves are used as not to interfere with their wide opening.

I claim:

1. In a device of the character described, a support, a series of stiff display frames, a series of rigid intermediate frames each consisting of upper and lower horizontal hinge bars rigidly connected by an upright bar, and pin and socket connections pivotally connecting the hinge bars of said intermediate frames at their inner ends to the support to swing freely without axial movement and at their outer ends to the several display frames, said intermediate frames being detachable both from said support and from said display frame without disturbing the parts of said support or 100 of said intermediate frames.

2. In a device of the character described, a support having a series of pivot pin sockets at top and bottom, a series of intermediate frames each having a pivot pin at top 105 and bottom arranged in an axis near the inner edge of said frame and engaging a pair of said sockets, each intermediate frame also having a socket at top and bottom arranged in an axis near the outer 110

edge of said frame, and a series of stiff display frames each having a pivot pin at top and bottom engaging the sockets on the intermediate frame.

5 3. An intermediate frame for an index or display device of the character described, comprising a pair of hinge members spaced apart, each having a pivot pin at one end

and a socket at the other end, and a brace rigidly uniting said hinge members. 10

Signed by me at North Tonawanda, New York, this eleventh day of September, 1915.

JAMES H. RAND, JR.
